FRANK BERNARD FOLEY, OF INGERSOLL, ONTARIO, CANADA.

FEEDING MECHANISM FOR UPPERCUT APPLE-SLICING MACHINES.

1,161,466.

Specification of Letters Patent.

Patented Nov. 23, 1915.

Original application filed April 3, 1914, Serial No. 829,266. Divided and this application filed October 3, 1914. Serial No. 864,819.

To all whom it may concern:

Be it known that I, FRANK BERNARD FOLEY, of the town of Ingersoll, in the county of Oxford, in the Province of Ontario, Canada, have invented certain new and useful Improvements in Feeding Mechanisms for Uppercut Apple-Slicing Machines, of which the following is the specification.

My invention relates to improvements in feeding mechanisms for upper cut apple slicing machines described in my pending application, No. 829,266, filed April 3rd, 1914, the present application forming a division thereof and the object of the present invention is to devise a simple means for increasing the capacity of the feed for carrying the apples one at a time from the containing hopper into the pockets forming part of the slicing mechanism, which may be run at a normal rate of speed and which will, therefore, insure that no missing of the apples takes place in the hopper and no overthrowing of the apples occurs at a point of discharge, in which means are provided for insuring that the time of discharge of each apple from the feeding mechanism is coincident with the arrival of the pocket opposite the receiving point and in which a simple and easy means for taking up the slack of the elevator belt is provided and it consists essentially of a rectangular open frame, an adjustable upper driving shaft and a stationary lower idler shaft journaled in bearings carried by the frame, pulleys mounted upon the upper driving shaft and lower idler shaft, a conveyer belt mounted upon the pulleys, peculiarly constructed buckets carried by the belt and extending alternately from each edge thereof, a drive connection between the upper conveyer shaft and main shaft of the apple slicing machine, an inclined chute designed to receive the apples from the buckets and convey them to the slicing mechanism and a trip device designed to time the discharge of the apples from the bucket into the inclined chute as hereinafter more particularly explained by the following specification.

Figure 1, is a general perspective view of my apple slicing machine showing the feeding mechanism connected thereto. Fig. 2, is a vertical enlarged cross section through the feeding mechanism and adjacent portion of the apple slicing mechanism. Fig. 3, is a perspective detail of a portion of the elevat-

ing conveyer belt and buckets and adjacent parts. Fig. 4, is a sectional detail showing the means for supporting the adjustable sprocket pinion for taking up the slack of the sprocket driving chain. Fig. 5, is a front elevation of the feeding belt and bucket conveyers attached thereto showing the arrangement of the bucket conveyers.

In the drawings like letters of reference indicate corresponding parts in each figure.

In order to make the operation of my feeding device clear I will first describe in general terms the construction and operation of the slicing machine. This machine comprises a main frame 1 supporting a table 2 through the center of which extends a vertical rotatably mounted shaft 3 on the upper end of which is mounted the rotary member 4. On the rotary member 4 are suitably mounted a vertical series of outer and inner ring members 5 and 6 connected together by inter-connecting sweep arms 7. The arms 7 are semi-circular in form and are arranged one beneath the other in a rearwardly inclined position one to the other and form intervening pockets located between the outer and inner rings 5 and 6 and each set of sweep arms 7. The apples are designed to be fed into these pockets and to be carried against suitable slicing knives such as shown at 8. My feeding device is adapted to feed apples into these pockets so that one apple only is fed into each pocket and at the required time.

I will now describe my feeding mechanism. 9 is a rectangular frame. The frame 9 is composed of the four verticals 10, 11, 12 and 13, the verticals 10 and 11 being connected together by cross bars 14 and 15 and the verticals 12 and 13 by similar cross bars 16 and 17. The end portions of the frame formed by the verticals 10 and 11 and connecting bars 14 and 15 and verticals 12 and 13 and connecting bars 16 and 17 are connected together by longitudinal bars 19 and 20.

21 is a hopper secured in a stationary position between the verticals 10 and 11, 12 and 13 and to the connecting bars 15 and 17.

22 are bearing brackets secured to each cross bar 15 and 17.

23 is an idler shaft journaled in the bearing brackets 22 and 24 is a pulley secured to the shaft 23 intermediately of its length.

25 and 26 are supplemental cross bars, the cross bar 25 extending between the verticals 11 and 12.

10 and 11 at the inside thereof and the cross bar 26 extending between the verticals 12 and 13 at the inside thereof.

27 are vertical slots formed in each vertical member 10, 11, 12 and 13 in proximity to the upper end thereof.

28 are bolts extending through the slots 27 and through the cross bars 25 and 26. The bolts 28 are provided with suitable nuts and washers so as to allow of the cross bars 25 and 26 being clamped in position by the bolts 28 when adjusted vertically.

29 are vertical bolts extending through the cross bars 14 and 16 and into the cross bars 25 and 26. The cross bars 25 and 26 are hung by bolts 29 when the bolts 28 have been loosened.

30 are nuts threaded on to the upper end of the bolts 29 and by which the bolts are hung from the cross bars 14 and 16.

31 are bearing brackets carried by the cross bars 25 and 26.

32 is a shaft journaled in bearing brackets 31.

25 33 is a pulley secured to the shaft 32.

34 is a belt mounted upon the pulleys 24 and 33.

35 is the driving shaft of the apple slicing machine connected to the apple slicing machine by the gear pinion 36, and the annular gear 37 formed on the rotary member 4.

38 is a bevel pinion secured to the inner end of the driving shaft 35.

39 is a counter shaft secured in suitable bearings carried by the table 2 and provided at one end with a bevel gear 40 meshing with the bevel gear 38 and at the opposite end to the sprocket wheel 41.

42 is a sprocket gear mounted on the corresponding end of the conveyer shaft 32.

43 is a sprocket chain connecting the sprocket gear 43 and sprocket pinion 41 together.

44 is an idler sprocket pinion mounted upon a slide 45 slidably held in a groove 46 formed in the inner face of the cross bar 26.

47 is a slot also formed in the cross bar 26.

48 is a securing bolt extending through such slot into the slide 45 in order to secure 50 the slide in any position to which it may be adjusted.

49 and 50 are a pair of vertical boards having inclined upper edges on which is supported an inclined chute 51, the upper end of the chute extending in close proximity to the face of the conveyer belt 34, the opposite or lower end of the chute extending over the pockets formed between the sweep rings 5 and 6 hereinbefore described.

60 52 and 53 are two series of buckets extending alternately from the edges of the conveyer belt 34 to which they are attached by lugs 54 (see Fig. 3) riveted to the belt.

The body of the bucket is also provided 65 with a depending arm 55 which bears

against the vertical board 49 during the major portion of its upward travel in order to hold the bucket in a rigid and steady position as it travels upward. Each bucket is also provided with a slot 56 extending inwardly from the outer edge thereof. It will be understood by referring to Fig. 2 that as the buckets pass downwardly in the direction of arrow and around the pulley 24 that they engage with the apples and 75 convey them upward as indicated in this figure.

In order to insure that the time of discharge of each apple from each bucket is coincident with the arrival of each pocket 80 opposite to the lower end of the chute 51 I have provided the following tripping device: 57 is an inclined arm secured to the inner side of the bar 19 having a curved lower end 58 on to which is pivoted an arm 59, the upper end of which lies in the path of travel of the bucket slots 56 as indicated particularly in Fig. 3. 60 is a pin extending from the arm 57 in proximity to the lower end of the arm 59. 61 is a tension spring 85 connecting the lower end of the arm 59 to a suitable portion of the arm 57. As the apple is carried upwardly by the buckets it strikes the inwardly projecting end of the arm 59 which forces the apple inwardly out 95 of the bucket so as to be delivered into the chute 51. If the apple is small it is only struck by the extreme end of the arm 57 which discharges it. If the apple is a large apple the arm 59 is swung upwardly until 100 the tension of the spring serves to discharge the apple. The apple after being discharged into the tube 51 falls into one of the pockets of the apple slicing mechanism and is sliced as described in my previously filed application hereinbefore referred to.

Should the belt 34 of the conveyer become slack all that it is necessary to do is to loosen the bolts 28 and 48. The nuts 30 may then be tightened on the bolts 29 drawing the 110 cross bars 25 and 26 upwardly, the sprocket wheel 44 adjusting itself to a new position of the driving chain. After this adjustment has been made the bolts 28 and 48 may be again tightened. It will also be seen that 115 by securing the buckets 52 and 53 to the belt 34 so as to extend alternately from each edge thereof an increased feeding capacity is attained.

The great difficulty has been with a single 120 feeding device, that is to say, a device in which the buckets are attached to the face of the belt in a single series, is that such a device cannot be operated fast enough to give much capacity for the reason that when the 125 buckets pass too rapidly through the apples in the hopper they do not have time to engage an apple every time. Running at a high rate of speed will also cause the apples to be tossed in the air instead of de- 130

livering them into the chute 51. My feeding device can run at a normal rate of speed and yet have double capacity to the ordinary device. The buckets are also placed alternately on each side of the belt so that sufficient space is left between the buckets to receive the apple while passing through the bottom of the hopper.

What I claim as my invention is.

10 1. In a feeding device for upper cut apple slicing machines, the combination with the main hopper, of a bucket conveyer comprising upper and lower rollers, of an endless belt carried by the rollers, buckets secured at the edges of the belt having open inner sides, a discharge chute extending from the outer surface of the belt to deliver the apple into the sweep arm mechanism, and a vertical board extending downwardly flush with the sides of the inclined chute and against which the open sides of the buckets bear during their upward travel, as and for the purpose specified.

25 2. In a feeding device for upper cut apple slicing machines, the combination with the main hopper, of a bucket conveyer comprising upper and lower rollers, of an endless belt carried by the rollers, buckets secured at the edges of the belt having open inner sides, a discharge chute extending from the outer surface of the belt to deliver the apple into the sweep arm mechanism, and a vertical board extending downwardly flush with the sides of the inclined chute and against which the open sides of the buckets bear during its upward travel, and yieldable means for insuring of the discharge of the apple from the buckets at regular intervals into the chute when it arrives at the

discharge position, as and for the purpose 40 specified.

3. In a feeding device for upper cut apple slicing machines, the combination with the main hopper, of a bucket conveyer comprising upper and lower rollers, of an endless belt carried by the rollers, buckets secured at the edges of the belt having open inner sides, and having a slot extending inwardly from the outer side, a discharge chute extending from the outer surface of 50 the belt to deliver the apple into the sweep arm mechanism, and a vertical board extending downwardly flush with the sides of the inclined chute and against which the open sides of the bucket bears during its 55 upward travel, and a spring held pivoted arm designed to bear against the apple contained in the bucket as it passes upwardly and to enter the open slot as the apple is discharged over the upper edge of the inclined chute, as and for the purpose specified.

4. In a feeding device for upper cut apple slicing machines, the combination with a discharge chute, of a bucket conveyer comprising upper and lower rollers, an endless belt supported thereby so that the face of the belt bears against the upper end of the discharge chute, buckets secured to each edge of the belt alternately one with the other, and yieldable means for insuring of the discharge of the apples at regular intervals, as and for the purpose specified.
